UNITED STATES PATENT OFFICE.

JOHN HERMAN, OF LOS ANGELES, CALIFORNIA.

ORE-CRUSHER.

1,395,959.

Specification of Letters Patent.

Patented Nov. 1, 1921.

Application filed May 27, 1920. Serial No. 384,689.

To all whom it may concern:

Be it known that I, JOHN HERMAN, a citizen of the United States, residing at Los Angeles, in the county of Los Angeles and State of California, have invented new and useful Improvements in Ore-Crushers, of which the following is a specification.

This invention is an ore crusher having jaws movable relative to one another, and it is the object of the invention to provide a simplified and durable construction of very few parts.

The invention will be readily understood from the following description of the accompanying drawings, in which—

Figure 1 is a side elevation of the crusher, partly broken away.

Fig. 2 is a transverse section on the line 2—2 of Fig. 1.

Fig. 3 is a view, similar to Fig. 1, of a modified form of the invention.

Fig. 4 is a longitudinal section on the line 4—4 of Fig. 3.

The improved crusher comprises jaws 1 and 2 arranged in inclined upright position with the jaw plates 1' and 2' converging downwardly so as to progressively crush any material passing downwardly between the jaws. The jaws are arranged for movement toward and away from one another by means of an eccentric driving connection.

As an instance of this arrangement the jaw 2 is provided with bearings 3 and 4 at the respective ends thereof, these bearings being arranged in the surface of the jaw which is opposite the jaw plate 2'. The bearing 3 may be formed integral with the jaw while the bearing 4 is, preferably, a split bearing having a bearing cap 5. A shaft 6 extends through the bearing 4 and is provided with an eccentric portion 7 intermediate of the ends of said shaft which is arranged to engage bearing 4 in the jaw 2.

A shaft 8 extends through the bearing 3 at the opposite end of the jaw 2.

Bearings 9 and 10 are provided at the respective ends of jaw 1 in the surface of said jaw which is opposite the jaw plate 1', these bearings being, preferably, formed integral with the jaw. A shaft 11 extends through the bearing 9 at the upper end of jaw 1, and a shaft 12 extends through the bearing 10 at the opposite lower end of the jaw. The shafts upon which the jaws 1 and 2 are mounted project laterally beyond the jaws, and these end projections of shaft 6 are pro-

vided with eccentrics 13 which are diametrically oppositely arranged relative to eccentric portion 7. Bearing collars 14 are received around the respective end projections 60 of the shafts for the jaws, these bearing collars upon end projections of shaft 6 surrounding the eccentrics 13. A loop 19 extends around the bearing collars 14 upon each of the pairs of aligned end projections 65 of shafts 6 and 11 and 8 and 12. The shaft 6 beyond its end projections is, preferably, journaled in suitable bearings 15 carried by the frame of the machine, and in the embodiment of the invention illustrated in 70 Figs. 1 and 2, the ends of shaft 12 beyond its end projections is similarly journaled in bearings 16 carried by the frame of the machine. The shafts 8 and 11 are loosely mounted relative to the frame of the machine. A driving connection is provided for shaft 6 which may include a pulley 17 fixed upon said shaft beyond one of the bearings 15.

Cheek plates 18 are, preferably, secured 80 to opposite sides of the pair of jaws 1 and 2, these cheek plates being shown as bolted at 20 to the jaw 1 and as extending beyond jaw 2 with said extensions bolted together as shown at 21.

The shaft 6 being rotatable relative to the frame of the machine and the shaft 8 being free for movement relative thereto, when the shaft 6 is rotated the engagement of eccentric 7 with the bearing 4 of the jaw 2 will 90 cause movement of said jaw relative to the frame of the machine in both a reciprocating and swinging path of travel toward and away from jaw 1. The shaft 12 being rotatable relative to the frame of the machine 95 and the shaft 11 being free for movement relative thereto will cause the loops 19, from shaft 6 to shaft 11, to impart a swinging movement to the jaw 1 upon the shaft 12 as a pivot, this swinging movement of the 100 jaw carrying the latter toward and away from jaw 2. During this relative movement between the jaws 1 and 2 the loops 19 connecting shafts 12 and 8 will limit the movement of shaft 8 relative to the fixed 105 shaft 12 for maintaining the jaws in proper relation relative to one another.

In the modification of the invention illustrated in Figs. 3 and 4, a construction similar to that previously described is employed 110 with the exception of the mounting for shaft 12. In this exemplification of the invention

the shaft 12 is not journaled in bearings but the loop 19 connecting shafts 8 and 12 is journaled for oscillating movement.

As an instance of this arrangement a shaft 5 23 extends across the frame of the machine, and any one of a plurality of bearings 21, shown as half bearings formed in a plate 22 secured to the loop 19, are adapted to be received over shaft 23 for pivotally supporting the lower ends of the crusher jaws.

By the arrangement as thus described it will be seen that rotation of shaft 6 will actuate jaw 2, as previously described, and the movement of said jaw will rock the loop 15 19 which is journaled upon shaft 23 for causing oscillating movement of jaw 1, said oscillating movement of jaw 1 being also controlled by the loop 19 connecting shafts 6 and 11. It will be understood that positioning shaft 23 in various ones of the bearings 21 will vary the movement of jaw 1 relative to jaw 2.

Thus it will be seen that I provide a crusher of very few parts and in which both 25 jaws of the crusher are moved relative to one another, the driving means for the crusher actuating one of the jaws, which is provided with a driving connection to the other jaw.

The following advantages of my ore

crusher should be noted: the adjustability 30 of the angle of the jaws and of the oscillating movement; the lightening of weight by the elimination of the usual frame; accessibility of every part; ease of replacement of any broken parts; ease of sectionalization 35 for transportation; possibility of regulating the vertical component of the crushing stroke to force the feed; and balancing of the crushing strains so that the crusher works smoothly instead of rocking the foundation.

Various changes may be made without departing from the spirit of the invention as claimed.

What is claimed is:

A crusher comprising jaws movable relative to one another and arranged respectively for oscillatory movement and for combined oscillatory and reciprocatory movement, a driving connection at one end 50 of said jaws, a connecting loop at the opposite end of said jaws, and means for pivotally mounting said connecting loop intermediate of its ends.

In testimony whereof I have signed my 55 name to this specification.

JOHN HERMAN.
